HIS ATTORNEY

UNITED STATES PATENT OFFICE.

ANDERS CHATTSTROM, OF DAVENPORT, IOWA.

POSTHOLE-DIGGING MACHINE.

1,356,125.

Specification of Letters Patent. Patented Oct. 19, 1920.

Application filed June 12, 1919. Serial No. 303,748.

To all whom it may concern:

Be it known that I, ANDERS CHATTSTROM, a citizen of the United States, residing at Davenport, in the county of Scott and State of Iowa, have invented certain new and useful Improvements in Posthole-Digging Machines, of which the following is a specification.

My invention pertains to machines for digging post holes, of that class which are manually operated, and has for its purpose to increase the efficiency and ease of operation of such devices. It comprises primarily a vertical auger with operating mechanism therefor; means for guiding such auger; and means for cleaning the same and rendering the operation thereof less difficult, especially in hard earth. Means are also provided for adjusting the position of the supporting frame to the character of the ground upon which it stands, in case the same is not absolutely level.

In the drawings:—

Figure 1 is a plan view of my invention, 25 with portions thereof broken away.

Fig. 2 is a side elevation thereof.

Figs. 3 and 4 show the telescopic leg in different positions.

Fig. 5 shows a modified form of operating 30 mechanism for the machine.

Figs. 6 and 7 are, respectively, plan and edge views of the plate 11.

Figs. 8 and 9 show the cleaning tool 12 in edge and side views.

The frame of the machine consists of a plate 1, supported by legs 2, one of which is provided with a telescopic section 3, provided at its lower end with a perforated foot 4, to receive a spike 5. The other legs are 40 turned at their lower ends into perforated feet 6, also adapted for use in spiking the frame to the ground. The parts of the telescopic leg are capable of being fixed in adjusted positions by means of a set-screw 3^a, 45 seated in the part 3. When the frame is located on ground having an inclined surface the telescopic leg is lengthened or shortened so as to conform thereto, and hold the plate 1 in a horizontal position.

The plate 1 is provided with a central threaded bearing 7, in which a screw 8 has vertical play, the upper end of such screw having a hand-bar 9 for operation. The screw 8 is projected downwardly into an 55 auger 10, of suitable dimensions for excavating the earth to form a hole of desired

size. Mounted on the legs 2 at a distance below the plate 1 is a plate 11, provided with a central opening 12' through which the auger 10 passes, the size of the opening being very little greater than the diameter of the auger, so as to limit the movement of such auger laterally. A set of the plates 11 can be provided with different sized openings, as indicated in broken lines in Fig. 6, 65 to conform to augers of varying diameters which are used in the machine.

Just beneath the plate 11 a scraper 12 is pivotally supported, as at *a*, and provided with a handle 13. The blade of the scraper, 70 when swung inwardly, is in proximity to the spiral blade of the auger, and aids in keeping the same free from dirt. When it is not desired to use the scraper it can be turned to one side by means of the handle 75 13, as shown in broken lines in Fig. 1. Mounted on the plate 11 is a receptacle 14 provided at its lower end with a valve-controlled nozzle 15. Said receptacle is intended for a supply of water, to be furnished 80 to the auger when in operation, wetting and dissolving the earth, and rendering the operation of the auger less difficult.

The operation of the screw rotates the auger, and at the same time forces it gradually into the ground, similarly to devices of that kind now in use, the plate 11 holding the auger and frame in steady position with relation to each other. Said plate not only acts as a guide for the auger, but it also 90 furnishes a brace for the legs, a support for the scraper, and a support for the water receptacle.

In Fig. 5 the screw 8 is shown provided at its upper end with a bevel-gear wheel 16, 95 in mesh with a gear-pinion 17 on a shaft 18 supported from the upper end of the screw. The outer end of said shaft has fixed thereto a crank 19 by means of which it can be operated. The operation of the shaft is imparted through the wheels 17 and 16 to the screw 8, to cause a rotation thereof.

What I claim and desire to secure, is:

1. A device of the class described, comprising a frame; a screw vertically operable 105 in said frame; an auger operatively connected with said screw; a guide-member for said auger mounted in said frame; and a scraper pivotally mounted in said machine and adapted to be brought into proximity 110 with said auger.

2. A device of the class described, com-

- prising a plate and supporting legs therefor; a screw vertically movable in said plate; an auger on the lower end of said screw; an auxiliary plate mounted on said legs and provided with a central opening for said auger; and a water supply receptacle mounted on said auxiliary plate and adapted to direct a stream of water upon said auger.
- 5 3. A device of the class described, comprising a frame, provided with supporting legs; a screw mounted in said frame so as to be vertically movable therein; an auger on the lower end of said screw; and an auxiliary supporting member mounted in said frame and furnishing a guide for said
- 10
- 15

auger; one of said legs being telescopically formed, and capable of being held in adjusted positions.

4. A device of the class described, comprising a plate and supporting legs therefor; a screw vertically movable in said plate; an auger operatively connected with said screw; an auxiliary plate mounted on said legs and provided with a central open- 20
ing, forming a guide for said auger; a scraper pivotally mounted on the lower face of said auxiliary plate; and a water supply receptacle mounted on said auxiliary plate and provided with a suitable outlet. 25

In testimony whereof I affix my signature. 30
ANDERS CHATTSTROM.
